US0D1022719S

(12) **United States Design Patent** (10) Patent No.: **US D1,022,719 S**
(45) Date of Patent: ** Apr. 16, 2024

(54) **CONFIGURATION APPLIED TO RADAR EQUIPMENT**

(71) Applicant: **PERKONS S/A**, Pinhais (BR)

(72) Inventors: **Adriel Bilharva Da Silva**, Curitiba (BR); **Rodrigo Augustinho Fonseca**, Curitiba (BR); **Juliano Rodrigo Ribeiro De Freitas**, Araucaria (BR); **Paulo Roberto Cemin**, Curitiba (BR); **Guilherme Riesemberg Bastos Silva**, Curitiba (BR); **Icaro Pierre Schmitz Freddo**, Curitiba (BR); **Rodrigo Trebien**, Curitiba (BR)

(73) Assignee: **Perkons S.A.**, Pinhais (BR)

(**) Term: **15 Years**

(21) Appl. No.: **29/835,299**

(22) Filed: **Apr. 18, 2022**

(30) **Foreign Application Priority Data**

Oct. 18, 2021 (BR) 3020210051214

(51) LOC (14) Cl. **10-04**

(52) U.S. Cl.

USPC **D10/65**; D10/78; D10/98

(58) **Field of Classification Search**

USPC D10/65, 78, 98

CPC G01S 13/581; G01S 13/92

(57) **CLAIM**

The ornamental design of a configuration applied to radar equipment, as shown and described.

DESCRIPTION

FIG. 1 is a perspective view of a preferred embodiment.

FIG. 2 is a front view of the preferred embodiment.

FIG. 3 is a rear view of the preferred embodiment.

FIG. 4 is a left side view of the preferred embodiment.

FIG. 5 is a right side view of the preferred embodiment.

FIG. 6 is top view of the preferred embodiment.

FIG. 7 is a bottom view of the preferred embodiment.

FIG. 8 is a perspective view of the preferred embodiment.

FIG. 9 is a perspective view of the preferred embodiment; and,

FIG. 10 is a perspective view of the preferred embodiment.
